UNITED STATES PATENT OFFICE.

GEORGE L. BENNETT, OF CLEVELAND, OHIO.

STRUCTURAL COLUMN.

Application filed February 1, 1926. Serial No. 85,104.

My invention relates to structural columns, and more particularly to a column encasement formed of sheet metal.

In structural steel work it is the custom 5 to provide structural steel or cast iron columns with enveloping fireproofing material and to provide a plaster surface finishing for such columns. Such fireproofing material is ordinarily molded to the structural steel or 10 cast iron column by the use of knock-down forms.

With the above conditions in mind, I have provided a structural column embodying therein a light sheet metal encasement enclosing the structural steel, or cast iron, column and not only serving as a form to facilitate the application and retention of the fireproofing material between same and the structural steel or cast iron column at all 20 times, but imparting a surface finish to the column sufficiently smooth to avoid the necessity for a plaster finish exteriorly of the completed column.

This encasement may be made of a single 25 fairly light sheet of metal, thus permitting it to be readily sprung, to position it in relation to the structural steel or cast iron column, or in complementary sections, adjacent edges of the sheet or of the sections forming 30 the column being provided with co-operating interlocking devices which with the closing of the encasement when applying it to the column, will engage each other in a manner to aline and hold the adjacent edges of the 35 sheet metal or of adjacent sections of encasement in close abutting relation.

The encasement itself affords no appreciable support for the building structure and is designed primarily to facilitate the finishing 40 of the columns of a building and ensure durability as to the finish of these columns. While the use of the exterior of the encasement will afford a sufficiently attractive finish to avoid the necessity for applying a 45 superficial dressing of plaster thereto, of course, such surface finish may be used, if desired.

The invention consists primarily in a structural column embodying therein a sheet 50 metal encasement of substantially the same height as, and adapted to inclose a structural metal column, and a filling about said column, said encasement having a parting extending for the full height thereof, and co-operating interlocking members secured to the material of said encasement adjacent and

upon opposite sides of said parting and within said encasement whereby portions of said encasement, with the closing thereof at said parting, will be mechanically united with 60 the edges of the parting in close abutting relation; and in such other novel features of construction and combination of parts as are hereinafter set forth and described, and more particularly pointed out in the claims hereto 65 appended.

Referring to the drawings,

Fig. 1 is an elevation of a portion of a column embodying my invention, with parts thereof broken away; 70

Fig. 2 is a section on the line 2—2 of Fig. 1;

Fig. 3 is a view similar to Fig. 1, of another embodiment of the invention;

Fig. 4 is a section on the line 4—4 of Fig. 3; and 75

Fig. 5 is a detail view of another form of interlocking mechanism for securing the edges of the sheet metal of the encasement together adjacent a parting of the encasement. 80

Like letters refer to like parts throughout the several views.

In the embodiment of the invention shown in the drawings, the use of an encasement 85 formed of a plurality of interlocked sheet metal sections and of an encasement formed of a single sheet metal section, with the edges of each section adjacent the parting provided with interlocking members, is illustrated. 90

Referring more particularly to the embodiment of the invention shown in Figs. 1 and 2, a steel column *a* of the usual construction is shown, this column being inclosed by a sheet metal encasement composed of a plurality of, or two, sections *b* and *c*, the relative dimensions of the column and the encasement being such as to form a space about the column *a* for the reception of a suitable 95 filler of fireproofing or other material or objects *d*. To facilitate the installation of said encasement, there are two partings, or if the number of sections be greater than two, partings corresponding with the number of said sections, these partings extending for the entire length or height of the encasement. 100

The sections are held together adjacent these partings by means of an interlocking mechanism which is concealed as a result of its being located upon the face of the sheet metal of the encasement presented towards 110

the column *a*. The interlocking mechanism adjacent each parting of the encasement is identical with that of the other parting, and the number of these mechanisms and their vertical spacing with relation to each other, will vary with columns of different heights and encasements of different weights. A description of but one of these interlocking mechanisms is therefore necessary, since the other mechanisms are mere duplicates thereof.

Carried by the sheet metal of the encasement upon one side of the parting and projecting from the edge thereof a distance sufficient to lap the edge of the material upon the opposite side of said parting, is a socket plate *e* preferably secured in position with relation to the metal of the encasement by being spot welded thereto.

Secured to the sheet metal of the encasement at the other side of the parting in any desired manner as by spot welding, is a spring latch member *f* having a tooth *g* adapted to enter the socket in the member *e*, the latch member adjacent said toothed member having an offset portion *h* forming a pocket to receive the projecting end of the socket plate *e*. Preferably the end of the latch member *f* and the tooth *g* are provided with a bevel *i* which with the closing of the portions of the encasement adjacent said parting with relation to each other will, by engagement with the edge of the socket member *e*, cause said socket member to spring the latch member *f* sufficiently to ensure the automatic engagement of the tooth *g* with said socket member when the edges of the encasement adjacent the parting are in substantially abutting relation to each other.

This automatic action of the interlocking mechanism is preferable as it very much simplifies the assembling of the encasement with relation to the column *a*. If desired, however, the interlocking mechanism may be constructed as illustrated in Fig. 5 of the drawings, in which the socket plate *e'* is of the construction as heretofore described and the latch member *f'* instead of being provided with a beveled end and tooth, has a squared tooth *g'*. With this construction, however, it will be necessary to manually flex the projecting spring latch member *f'* when finally closing the encasement about the column.

In the embodiment of the invention shown in Figs. 3 and 4 of the drawings, the encasement is made of a single section *b'* of sheet metal so bent as to approximate the form of the complementary encasement sections *b* and *c* shown in Figs. 1 and 2. This section has a single parting only, and is provided adjacent this parting with an interlocking mechanism constructed and operating in the same manner as the interlocking mechanism described in connection with the construc-

tion shown in Figs. 1 and 2. The socket member of this interlocking mechanism is shown at *e*², the latch member at *f*², the offset or socket forming alining portion at *h*², the tooth at *g*² and the bevel at *i*².

The effects secured by both forms of the invention illustrated in the same, that shown in Figs. 1 and 2 being especially adapted for use with an encasement formed of heavier sheet metal, and that shown in Figs. 3 and 4 being adapted for use with an encasement formed of lighter sheet metal.

In practice, when using a multiple part encasement, the different parts thereof are positioned in relation to the column *a*, and the adjacent edges of the section, or sections, at the line of parting, are brought together with the socket plate *e*, *e'*, carried by the encasement at one side of a parting positioned between the spring latch member *f* or *f'*, and carried by said encasement at the other side of the parting. When the edges are so positioned, they are forced together, the offset portion *h* or *h'* receiving the socket plate *e* or *e'* and accurately alining the adjacent edges of the sheet metal forming the encasement upon opposite sides of said parting. As the gap at the parting is closed, the bevelled portion *i* of the latch member *f* and the tooth *g*, will, by engagement with the plate *e*, cause the springing of the latch member inwardly, so as to cause the tooth to enter the socket in said plate *e*, and thus firmly lock the edges of the encasement at the parting.

The encasement as a whole may then be accurately located with relation to the inclosed column *a* and the filler, such as fire-proofing material, introduced in the space between the column *a* and the encasement.

If a squared tooth *g'* is used of course it will be necessary to force this tooth inwardly to permit it to pass the socket plate.

As to the form of the invention shown in Figs. 3 and 4, it is necessary to open the previously formed encasement section sufficiently to permit it to pass about the column *a* and then bring the edges of the sheet at the parting together and close them with relation to each other, the interlocking mechanism acting the same in this form of the invention as in the multiple section encasement.

When the encasement is once in position, the edges of the sheet metal at the parting, whether there be a single or a plurality of partings, will be brought into abutting relation in substantially accurate alinement, with these adjacent edges permanently locked in relation to each other, it being contemplated that while this encasement shall serve as a form to facilitate the introduction of fire-proofing or other filler between it and the column, it shall also serve as facing sheathing for the completed column. The inter-

locking mechanism when positioned within the column is not only protected by the sheet metal of the encasement but is also effectively blocked against possible accidental release by the material between the encasement and the column.

It is preferable to so form the socket plate e , e' or e^2 as to have it conform to the configuration of the sheet metal of the encasement adjacent thereto, and to the contiguous edge of the sheet beyond the parting, so that this plate in projecting across the parting will serve as an alining member with relation to both edges of the material at the parting and will prevent outward movement at the edge adjacent which the socket plate is secured with relation to the other edge, the latch member acting upon the socket plate to prevent the outward movement at the edge of the encasement adjacent which the latch member is secured.

The encasement, while formed of fairly light sheet metal stock, when positioned relation to a column a possesses sufficient rigidity to be effective as a protecting sheathing, the filler between same and the column a being protected thereby while at the same time affording a backing therefor which will prevent possible displacement of the encasement with relation to the column.

It is not my intention to limit the invention to any configuration of the encasement, and if desired the sheet metal forming the encasement may have impressed thereon decorative matter.

The number of interlocking mechanisms may be varied at will, their number and position being more or less controlled by an anticipated tendency of the separation at the edges of a parting. I secure the parts of such mechanisms by spot, or other, welding methods and position these parts within the encasement in order to avoid defacement of the exposed face of the encasement by parts protruding therefrom.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. A structural column embodying therein a sheet metal encasement of substantially the same height as and adapted to inclose a structural metal column, and a filling about said column, said encasement having a parting extending for the full height thereof, and co-operating interlocking members secured to the material of said encasement adjacent and upon opposite sides of said parting and within said encasement whereby portions of said encasement, with the clos-

ing thereof at said parting, will be mechanically united with the edges of the parting in close abutting relation.

2. A structural column embodying therein a sheet metal encasement of substantially the same height as, and adapted to inclose a structural metal column, and a filling about said column, said encasement having a parting extending for the full height thereof, a socket plate carried by and within said encasement at one side of the parting, and a toothed spring member carried by and within said encasement at the other side of said parting and in engaging relation with said socket plate, whereby portions of said encasement, with the closing thereof at said parting, will be mechanically united with the edges of the parting in close abutting relation.

3. A structural column embodying therein a sheet metal encasement of substantially the same height as, and adapted to inclose a structural metal column, and a filling about said column, said encasement having a parting extending for the full height thereof, a socket plate projecting beyond the edge of and lapping the parting, carried by and within said encasement at one side of the parting, and a toothed spring member carried by and within said encasement at the other side of said parting and in engaging relation with said socket plate, said spring member being offset with relation to the encasement to receive said socket plate, whereby portions of said encasement, with the closing thereof at said parting, will be mechanically united and will be alined one with the other with the edges of each parting in close abutting relation.

4. A structural column embodying therein a sheet metal encasement of substantially the same height as, and adapted to inclose a structural metal column, and a filling about said column, said encasement having a parting extending for the full height thereof, a socket plate projecting beyond the edge of and lapping the parting, carried by and within said encasement at one side of the parting, and a toothed spring member carried by and within said encasement at the other side of said parting and in engaging relation with said socket plate, said spring member being offset with relation to the encasement to receive said socket plate, said spring member and said tooth being bevelled, whereby said spring member will be automatically engaged with said socket plate with the closing of said encasement, and portions of said encasement, with the closing thereof at said parting, will be mechanically united and will be alined one with the other with the edges of each parting in close abutting relation.

5. A structural column embodying therein a preformed arcuate sheet metal encasement

- of substantially the same height as, and adapted to inclose a structural metal column, and a filling about said column, said encasement having a parting extending for the full height thereof, an arcuate socket plate projecting beyond the edge of and lapping the parting, carried by said encasement at one side of the parting, and upon the side of said encasement presented toward said metal column, and an arcuate toothed spring member carried by said encasement at the other side of said parting and in engaging relation with said socket plate, said spring member being offset with relation to the encasement to receive said socket plate, and upon the side of said encasement presented toward said metal column, whereby portions of said encasement, with the closing thereof at said parting, will be mechanically united and will be alined one with the other with the edges of each parting in close abutting relation.
8. A structural column embodying therein a sheet metal encasement of substantially the same height as, and adapted to inclose a structural metal column and a filling about said column, said encasement comprising a plurality of complementary sections, the parting between adjacent sections extending for the full height thereof, a socket plate carried by and within one edge of each section and projecting therebeyond and lapping the parting between it and the adjacent section, and a toothed spring member carried by and within said adjacent section at the other side of the parting and in engaging relation with said socket plate, said spring members being offset with relation to the section carrying same to receive said socket plates, said spring members and said teeth being bevelled, whereby said spring members will be automatically engaged with said socket plates, and said sections of the encasement with the closing thereof at said partings will be mechanically united and will be alined one with the other with the edges of each parting in close abutting relation.
9. A structural column embodying therein a preformed sheet metal encasement adapted to inclose a structural metal column and a filling about said column, said encasement comprising a plurality of arcuate complementary sections, the parting between adjacent sections extending for the full height thereof, a socket plate carried by one edge of each section, upon the side of said section presented toward said metal column, and projecting therebeyond and lapping the parting between it and the adjacent section, and a toothed spring member carried by said adjacent section at the other side of the parting, upon the side of said section presented toward said metal column, and in engaging relation with said socket plate, said spring members being offset with relation to the section carrying same to receive said socket plates, whereby said sections of the encasement with the closing thereof at said partings will be mechanically united, will be alined one with the other with the edges of each parting in close abutting relation, and said spring members will be concealed within said encasement.
7. A structural column embodying therein a sheet metal encasement of substantially the same height as, and adapted to inclose a structural metal column and a filling about said column, said encasement comprising a plurality of complementary sections, the parting between adjacent sections extending for the full height thereof, a socket plate carried by and within one edge of each section and projecting therebeyond and lapping the parting between it and the adjacent section, and a toothed spring member carried by and within said adjacent section at the other side of the parting and in the engaging relation with said socket plate, said spring members being offset with relation to the section carrying same to receive said socket plates, whereby said sections of the encasement with the closing thereof at said

In witness whereof I have hereunto affixed my signature this 23rd day of January, 1926.

GEORGE L. BENNETT.
